UNITED STATES PATENT OFFICE

2,470,396

SPUR SHORE

Joseph D. Guerette, Brunswick, Maine

Application November 14, 1944, Serial No. 563,431

1. Claim. (Cl. 248-354)

1 My invention relates to improvements in so-called spur shores such as are used in ship launching ways to brace the ground ways, the primary object in view being to provide a simple form of lasting brace to take the place of the usual wooden spur shores, and which is easier to apply, without nailing, quicker to install, adapted for extension and contraction, as occasion may require, and is inexpensive to manufacture.

Other and subordinate objects, also comprehended by my invention, together with the precise nature of my improvements and the advantages thereof, will be readily understood when the succeeding description and claim are read with reference to the drawings accompanying and forming part of this specification.

In said drawings:

Figure 1 is a view partly in transverse section and partly in rear elevation illustrating my improved spur shore applied in a ship way,

Figure 2 is a view in side elevation of the spur shore of my invention detached,

Figure 3 is a view in plan,

Figure 4 is a view in longitudinal section, taken on the line 4-4 of Figure 3, and drawn to an enlarged scale, and

Figure 5 is a view in transverse section, taken on the line 5-5 of Figure 4.

Referring to the drawings by numerals, my improved spur shore, as shown, comprises a pair of telescopically arranged pipe sections including a female section 1 and a male section 2, having inner ends telescoping for a distance suitable for a purpose presently clear, said sections 1, 2 being provided with outer flat ends 3, 4 of double thickness of the metal from which the sections are formed and inclining laterally of said sections toward one and the same side of the device with rounded terminals 5, 6.

The female section 1 is provided with a longitudinal slot 7 therein and with a pair of elongated external flanges 8 extending along opposite sides of said slot 7. A substantially oval cam 9 is swingably mounted between the flanges 8 by a pivot pin 10 extending through one end of said cam 9 and into said flanges 8. The cam 9 is arranged to extend through the slot 7 into the female section 1 and to be swung inwardly of said section 1 to slidably engage the other end of the cam with the inner end of the male section 2 so as to force said sections 1 and 2 apart and extend the length of the spur shore. A handle 11 is provided on the cam 9 to abut the female section 1 when said cam is swung inwardly and

thereby establish the limit of inward movement of the cam.

A presser plate 12 of L-shape in cross section is swingably mounted on the end 3 of the female section 1 by means of a pair of laterally spaced ears 13 on the back of said plate, and a pivot pin 14 extending through said ears and through the terminal 5 of said end 3. The presser plate 12 is provided, as shown in dotted lines in Figure 2, with a pair of diverging bottom prongs 15 terminating in right angled teeth 16.

The outer end 4 of the male section 2 is provided with an anchor plate 17 swingably mounted on said end 4 by means of a pair of laterally spaced ears 18 on the back of the plate, and a pivot pin 19 extending through said ears and the terminal 6 of said end 4. The anchor plate 17 is provided with a plurality of bottom calks 19. The anchor plate 17 is preferably of elongated rectangular form and arranged to extend endwise longitudinally of the section 2. The calks 20 are preferably arranged in pairs laterally spaced and located adjacent opposite ends of said plate 17.

In Figure 1 of the drawings, my improved spur shore has been shown as applied in a conventionally illustrated ship launching way, 21 designating the usual ground ways, 22 the usual sliding ways for supporting a ship hull 23, and 24 the usual ribbons or guides extending along the upper outer corners of the ground ways 21 and which present right angled outer lower corners 25. As clearly shown in said figure, the shores are applied with the presser plate 12 fitted over said corners, or edges, 25 so that the prongs 15 underlie said ribbons and the teeth 16 will bite into the same, the sections 1, 2 being extended downwardly and laterally with the anchor plate 17 resting on the flooring 26 of the way and the calks 19 thrust into said flooring. As will be apparent, by means of the cam 9, the sections 1, 2 may be extended to tighten the presser plate 12 against the ribbons 24 and thrust the calks into the flooring 26. By swinging the cam 9 outwardly of the female section 1, the male section 2 will be released so that said section may be contracted to facilitate removal of the device.

As will be observed in Figure 4, the cam 9 is arranged so that under end thrust of the male section 2 against the camming end of the cam, it will be swung inwardly of the section 1 into an overthrow past dead center position in its limit of movement inwardly of said section 1, whereby said cam is prevented from working outwardly of the section, into a releasing position, but may be

swung into releasing position by means of the handle 11.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claim.

What I claim is:

A device of the class described for forming a brace between the floor of a ship way and an upper edge of a ground way comprising a pair of pipe sections having telescoping inner ends whereby the device is adapted to be extended and contracted, a right angled pressure plate on the outer end of one section adapted to fit against said edge, an anchor plate on the outer end of the other section adapted to bite into said floor, said angle plates being swingable about axes transverse to that of the pipe sections for compensating movement to fit against said edge and floor, and means to extend said sections to tighten said plates comprising a cam swingable in one

section for camming engagement with the inner end of the other section, said cam being constructed and arranged to be swung inwardly of said one section under thrust of the other section against the said cam and into an overthrow past dead center position against said one section whereby said cam is prevented from swinging out of camming engagement with the inner end of the said other section.

JOSEPH D. GUERETTE.
